DESIGN FOR A COMBINED EYE SHADOW AND ROUGE CASE

Elizabeth N. Graham, New York, N. Y.

Application September 11, 1947, Serial No. 141,315

Term of patent 14 years

(Cl. D86—10)

To all whom it may concern:

Be it known that I, Elizabeth N. Graham, a citizen of the United States of America, residing in New York city, county of New York and State of New York, have invented a new, original, and ornamental Design for a Combined Eye Shadow and Rouge Case, of which the following is a specification, reference being had to the accompanying drawing, forming part thereof, wherein:

I claim:

The ornamental design for a combined eye shadow and rouge case, substantially as shown.

ELIZABETH N. GRAHAM.
